UNITED STATES PATENT OFFICE.

JOHN ROGERS FLANNERY, OF PITTSBURGH, PENNSYLVANIA, ASSIGNOR TO FLANNERY BOLT COMPANY, OF PITTSBURGH, PENNSYLVANIA, A CORPORATION OF DELAWARE.

METHOD OF MAKING STAY BOLTS.

Application filed March 18, 1921. Serial No. 453,219.

To all whom it may concern:

Be it known that I, JOHN ROGERS FLANNERY, a citizen of the United States, and a resident of Pittsburgh, in the county of Allegheny and State of Pennsylvania, have invented certain new and useful Improvements in Method of Making Stay Bolts; and I do hereby declare the following to be a full, clear, and exact description of the invention, 10 such as will enable others skilled in the art to which it appertains to make and use the same.

This invention relates to an improvement in the manufacture of staybolts for boilers, 15 one object of the invention being to produce a staybolt for steam boilers, made from a solid bar having a head formed preferably forged, at one end and provided with a small central bore drilled longitudinally 20 through the bolt, said drilled bore extending from end to end thereof and through the previously formed head, and to provide for the closing of one or both ends of the bore.

With these and other objects in view, the 25 invention consists in certain features as hereinafter set forth and pointed out in the claims.

In the accompanying drawings, Figure 1 is a view of a solid bar from which the bolt 30 may be made; Figure 2 is a view showing the head formed on the solid bar or blank, and Figure 3 is a view showing a completed staybolt having a central longitudinal bore extending from end to end of the same and 35 closures for the ends of said bore.

My present invention contemplates an improvement upon the method and article covered by my present Patent No. 1,336,213, granted April 6th, 1920, wherein a tell-tale 40 bore is drilled longitudinally through the bolt and made to terminate within the previously formed head, and to avoid the necessity of accurately calculating the duration of the drilling operation to insure the termination of the tell-tale bore at a proper point within the formed head. Tell-tale holes or bores in staybolts are quite small in diameter and prior to the invention disclosed in my said former patent, the drilling 45 of tell-tale holes in staybolts, which would extend throughout the length of the body portion of long boiler staybolts had

not been successfully accomplished, but in said patent, the holes were made to terminate within the formed head at the outer end 55 of the bolt. Experiment has developed the fact that the bores or longitudinal holes may be drilled completely from end to end of the bolt and therefore entirely through the headed end thereof, but it is important that such drilling operation shall be performed after the head shall have been formed at the end of the bar or blank in order to avoid closing of a prohibitive portion of the bore which would be liable to happen if the 60 forming be done subsequently to the drilling of the hole.

In accordance with my present invention, I take a solid bar or blank 1 of suitable metal and at one end of said bar or blank, I form 70 a head 2 such for example as employed for a staybolt of the "flexible" type. After the head 2 has been formed, I drill a small central bore 3 throughout the length of the body of the bolt and completely through the head 75 2, by means of apparatus such, for example, as described in my former patent hereinbefore identified. After the bore shall have been thus drilled through the body of the bolt and its formed head, its outer end will 80 be closed by inserting thereinto, a plug 4 and this plug may constitute a permanent closure. The inner or fire-box end of the tell-tale bore may also be closed by a plug 5 to prevent the entrance of dust, scale or 85 other foreign solid matter which might clog said bore, and this plug 5 may constitute a removable closure for the inner end of the tell-tale bore.

Having fully described my invention what 90 I claim as new and desire to secure by Letters-Patent, is:—

1. The herein described method of making a staybolt, consisting in forming a head at one end of a solid bar of metal, then drilling a hole longitudinally through the bolt thus formed and causing said hole to extend throughout the full length of the body of the bolt and completely through its formed head, and inserting a closure in the 100 head to close the outer end of said hole.

2. The herein described method of making a staybolt, consisting in forming a head at one end of a solid bar of metal, then drill-

ing a hole longitudinally through the bolt thus formed and causing said hole to extend throughout the full length of the body of the bolt and completely through the head, 5 and inserting closures into both ends of said hole.

In testimony whereof, I have signed this

specification in the presence of a subscribing witness.

JOHN ROGERS FLANNERY.

Witness:

EDWIN S. RYCE.
